(57) **CLAIM**

The ornamental design for a hole-drilling tool, as shown and described.

DESCRIPTION

FIG. 1 is a perspective view of the hole-drilling tool showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof.

The broken lines in the drawings illustrate portions of the hole-drilling tool that form no part of the claimed design.
